(57) **CLAIM**

The ornamental design for a vehicle rear bumper lower extension, as shown and described.

DESCRIPTION

FIG. 1 is a front elevational view of a vehicle rear bumper lower extension showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a bottom, front and left side perspective view thereof; and,

FIG. 7 is a top, front and left side perspective view thereof. Areas surrounded by broken lines and shown in half-tone shading form no part of the claimed design.
